UNITED STATES PATENT OFFICE.

JOHN H. SHARP, OF CHICAGO, ILLINOIS.

CONTAINER.

Application filed November 22, 1919, Serial No. 339,907. Renewed April 26, 1923.

To all whom it may concern:

Be it known that I, JOHN H. SHARP, a citizen of the United States, residing at Chicago, in the county of Cook and State of

5 Illinois, have invented certain new and useful Improvements in Containers, of which the following is a description.

10 My invention belongs to that general class of devices known as containers, and relates more especially to what might be termed an interliner for closets, drawers, chests and the like, or be built up to make a chest in itself. It has particularly as an object the production of a container made of material 15 which will be suitable for receiving wearing apparel and other articles and protect them against the inroad of moths and other vermin. My improved container or lining is of sectional construction so that it may be fitted to various closets, boxes, drawers and the like, to secure the desired capacity. It may also be knocked down and transported from place to place. That is to say it may be installed by a renter or tenant in 20 a building when used in the closet, and thereafter be taken down and transported to some other building. It has among its further objects the production of a device of the kind described, that is simple, convenient, durable, efficient, ornamental and 25 satisfactory for use wherever found applicable. Many other objects and advantages of the construction herein shown and described will be obvious to those skilled in the 30 art, from the disclosure herein given.

35 To this end my invention consists of the novel construction, arrangement and combination of parts herein shown and described and more particularly pointed out in the 40 claims.

45 In the drawings, wherein like reference characters indicate like or corresponding parts,

Figure 1 is a perspective view of a closet partially equipped with my improved device.

Figure 2 is a sectional view through the walls of the same.

Figure 3 is a perspective view of a drawer equipped with my improved device.

50 Figure 4 is the perspective view of a simple form of fastening member for securing the sections together.

Figure 5 is a sectional view through two sections, showing one of the members in use.

55 Figure 6 is a perspective view of a similar construction.

Figures 7, 8, 9, 10 and 11 are sectional views illustrating modified forms of fastening means, and

60 Figure 12 is a perspective view of a portion of a modified form of section arranged with a shelf support.

65 Referring to the drawings, 1 represents suitable panels or sections of the desired size, shape and material. Ordinarily the sections will be made of wood, cedar being preferred, but they may be made of any other material suitable for the purpose as, for example, a treated composition which would have a tendency to repel moths and 70 the like. In Figures 1 and 2, I have shown corner pieces 2 which give a pleasing finish, may be easily cleaned, and are easily applied. The corner sections 2 are also made with the desired shape and size, it being understood all of the sections 1 and 2 need not be of the same size and shape. A corner piece 3, where three walls come together, may also be provided. In Figure 1 75 the closet is shown only partially lined. Where desired, the door 4 may also be lined or covered with suitable composition so that the completed closet is entirely enclosed and protected when the door is shut. The several sections described may be secured together in any suitable manner, several methods of fastening being illustrated. Referring first to Figure 4, 5 represents a plate of suitable material, size and shape, 80 which is provided with the desired number of pins 6, the same being adapted to fit into recesses 7 in the sections, as shown in Figure 5, when the sections are assembled. It 85 will be noted by referring to Figure 5 that the pins or lugs 6 are slightly inclined, the holes 7 being also inclined. Ordinarily the plate 5 need not be of great stiffness so that the plate may be sprung slightly in pushing the pins in place. When once sprung 90 into place the inclination of the pins and 95 spring in the plate causes them to be securely retained and the same also maintains the plate flush with the face of the sections. 100 This construction permits the sections, corners, etc., to be set up and detachably fastened together without tools, screws, nails, etc., and enables the lining to be set up, closely fitting the walls. In Figure 6 the plate 8 is shown with only two pins 6, it 105 being understood that the number of pins in the plates depend upon the particular places the same are used. The pins 6 may

110

be in the form of the pins 13 shown in Figure 8 if so desired.

In the construction shown in Figure 7, the sections 9 are secured together by pins 10 corresponding to dowl pins. In Figure 8 the sections 11 are shown secured together by fastenings consisting of a resilient plate 12, provided with a recess arranged to receive a pin 13 on a plate 14 secured to the edge of the adjacent section. In Figure 9 sections 14—14 are shown with dove-tailed grooves arranged to receive a locking strip or member 16 or the equivalent. In Figure 10 sections 17—17 are shown secured together by a plate 18 and screws 19. In Figure 11 sections 20—20 are shown with overlapping edges and secured together by a bolt 21.

In Figure 12, I illustrate a section 22 which may be provided with a flange 23. When it is desired to have a shelf in the closet, sections similar to 22 may be provided, the flanges 23 serving as shelf supports. These sections may also be used so that the flanges 23 form a door-stop. It will be obvious with all of the constructions that a closet may be easily lined. Where necessary the sections may be cut down so that, regardless of the size of the closet, the same may always be easily fitted. It is comparatively easy to set up the sections and secure them together, or to take them down for transporting. By making the sections of cedar or the equivalent any closet may be made suitable for the storing of furs, woolens and articles subject to attack by moths or other destructive agents. Or dressers, chiffoniers, wardrobes, trunks, and other storage receptacles may be interlined for the same purpose.

Having thus described my invention, it is obvious that various immaterial modifications may be made in the same without departing from the spirit of my invention. Hence I do not wish to be understood as limiting myself to the exact construction, arrangement, combination of parts and uses mentioned.

What I claim as new and desire to secure by Letters Patent is:

1. A knock down interliner of the kind described, adapted to be positioned within a container, said interliner comprising a plurality of sections of suitable material some of said sections adjacent one another being interchangeable and means for detachably securing all of said sections together.

2. A container comprising a plurality of interchangeable sections and corner sections, all of said sections constructed of material repulsive to vermin, the sections on opposite edges of each corner section being interchangeable, and means for detachably securing said sections together to provide a complete container.

3. A container comprising a plurality of interchangeable sections and corner sections, all of said sections constructed of material repulsive to vermin, the sections on opposite edges of each corner section being interchangeable, and means for detachably securing said sections together to provide a complete container, comprising a plurality of plates and means for connecting the plates with the adjacent sections. 75

4. A container comprising a plurality of interchangeable sections and corner sections, each section constructed of material repulsive to vermin and having a plurality of recesses in the face thereof, and means for detachably securing said sections together to provide a complete container, said means comprising a plurality of plates having pins secured thereto of a length to engage the sections in said recesses. 80

5. A container comprising a plurality of interchangeable sections and corner sections, all of said sections constructed of material of a vermin repelling nature, the sections on opposite edges of each corner section being interchangeable, and interchangeable means for detachably securing said sections together whereby substantially a complete container may be formed. 90

6. A container comprising a plurality of interchangeable sections and corner sections, all of said sections constructed of material of a vermin repelling nature, the sections on opposite edges of each corner section being interchangeable, and interchangeable means for detachably securing said sections together whereby substantially a complete container may be formed; comprising plates arranged at the faces of the sections and having means for engaging adjacent sections. 95

7. A container of the kind described and in combination, a plurality of interchangeable sections and corner sections, the sections on opposite edges of each corner section being interchangeable, and means for securing said sections together, comprising a fastening member provided with means for engaging adjacent sections, said engaging means constructed to maintain the securing means in place. 110

8. A container of the kind described and in combination, a plurality of interchangeable sections and corner sections arranged edge to edge, the sections on opposite edges of each corner section being interchangeable, and means for securing said sections together, comprising a fastening member provided with means for engaging adjacent sections, said engaging means constructed to detachably maintain the securing means in place. 120

9. A container comprising a plurality of interchangeable sections and corner sections, all of said sections being constructed of a 130

suitable material, and means for detachably securing said sections together to provide a complete container, comprising a plurality of plates, and pins secured to said plates at opposite sides thereof the pins at opposite sides of said plates being mutually inclined for connecting the plates with the adjacent sections.

In testimony whereof, I have hereunto signed my name in the presence of two sub- 10 scribing witnesses.

JOHN H. SHARP.
